UNITED STATES PATENT OFFICE.

JOHN R. L. SANTOS, OF BALTIMORE, MARYLAND, ASSIGNOR, BY MESNE ASSIGNMENTS, TO CHICAGO PNEUMATIC TOOL COMPANY, OF NEW YORK, N. Y., A CORPORATION OF NEW JERSEY.

PNEUMATIC TOOL.

Application filed December 15, 1922. Serial No. 607,184.

This invention relates to improvements in percussive tools and has for one of its objects to provide an improved tool wherein the motive fluid for operating the piston or plunger is controlled by a valve that is actuated in both directions by live air in distinction to being moved in one direction only by live air and in a reverse direction by compression that is produced by the piston or plunger on one of its strokes.

Another object of the invention is to provide an improved construction of tool wherein the piston or plunger may be either longer or shorter than its stroke.

15 A further object is to provide an improved structure wherein the valve, which controls the motive fluid that actuates the plunger may be subject to a constant live pressure from one direction and to a variable continuous live air-pressure to move it in a reverse direction.

A still further object of the invention is to provide a novel construction of valve and actuating means therefor whereby the valve 25 which has differential areas may be subjected to constant live motive pressure on both areas but in which the pressure on the larger area will be vented when the valve is to be moved by the pressure on the smaller area.

30 With these, and other objects in view, the invention is illustrated in the accompanying drawing, wherein,—

Fig. 1 shows a tool in longitudinal section in which the present invention is embodied,—the valve being down and the piston or plunger nearing the limit of its operating stroke.

Fig. 2 illustrates a similar sectional view through the tool,—the section however being taken in a plane at a right angle to that of the view in Fig. 1, and with the valve up and the piston or plunger nearing its return or up-stroke.

Fig. 3 shows the detached valve in side 45 elevation, and

Fig. 4 illustrates a vertical sectional detail through the detached valve-box.

It is to be understood that all of the views are more or less diagrammatic in that they 50 are made to illustrate the various ports, channels and passages in the several parts in the least number of views.

Referring to the drawing by reference numerals, 1 designates the barrel or cylinder of the tool having a chamber therein which con-

tains a piston or plunger 2. In the present instance the piston is shown with a length that is shorter than its stroke or shorter than one-half the length of the cylinder chamber, but this is not necessary and the invention is not to be so construed or restricted.

At the upper end of the cylinder there is provided a valve-box 3 with a valve 4 therein,—a disk 5 being interposed between the box and cylinder simply because the required ports and passages can be formed with more convenience when the disk and box are separate, as in this instance.

A cap 6 fits down over the box and disk and screws onto the upper end of the barrel 70 and thereby locks the several parts together.

At the lower end of the barrel there is provided a working tool 7, such for example, as a rivet-set and it is obvious that the piston or plunger, on its down or forward stroke, 75 will strike the tool 7 and thereby perform the work for which the particular tool is designed.

A live-air or motive-fluid supply-passage 8, extends through the cap so that a supply-hose (not shown) may be connected therewith and constantly supply live motive-fluid to said passage.

An exhaust passage 9 is provided through the valve-box and cap and opens to the atmosphere for the exhaust of fluid pressure, as and for a purpose that will presently be explained.

The cylinder is provided with a longitudinal channel 12, whose upper end opens through the disk 5, beneath the valve and 90 whose lower end opens into the cylinder-chamber in a plane adjacent to an exhaust port 10, which latter extends through the cylinder-wall to the atmosphere.

This channel 12, may best be identified by 95 the name valve lift-air-exhaust-channel because its function is to exhaust the continuously-supplied lift-air from beneath the valve by venting it to the atmosphere through the cylinder-chamber and exhaust port 10.

A passage 13 is provided in the valve-box 3, and the lower end of this passage, turns laterally and opens at the center of the box and at the under side of the valve 4.

The upper end of this passage 13 is in constant communication with a live-air supply, that will presently be explained, and for this reason I term this passage as a constant live-air valve-lift passage.

To distinguish the spaces in the cylinder 100

above and below the piston or plunger 2, I designate the upper cylinder space as chamber 14, and the lower cylinder space as chamber 15.

5 The cylinder 1, is further provided with what I term a piston or plunger lift-channel 16 which latter extends from the lower end of chamber 15, up into the valve-box 3 and turns inwardly to the center of the box where 10 it opens at the side of the valve 4.

The box 3 is provided near its top with an annular groove 17 and an upper chamber 18, while a so-called flip-chamber 20 is provided in the bottom of the box.

15 The box also has a passage 21 whose upper end opens into the upper annular groove 17 and whose lower end extends down to and communicates with the cylinder chamber 14 above the piston or plunger 2, as shown in 20 broken lines in Fig. 2 of the drawing.

The valve 4 has a central passage 22, which extends from the upper end thereof downwardly and then turns laterally and opens 25 around the exterior of the valve, and it will be noted that this annular groove 23 is located on the larger diameter of the valve.

The cap 6 is provided with an annular live-air supply channel 26 which latter is in constant communication with the live-air supply 8, and it is this channel 26, with which 30 the constant live-air valve-lift passage 13, is also in constant communication so that live air is constantly supplied to the larger bottom area of the valve 4.

The valve has a head 27, at its upper end which is designed to enter the upper box-chamber 18 and this head is always subject to live air-pressure from the supply passage 40 8, so that both ends of the valve 4 are constantly subject to direct live air that has not been used to do any work.

Operation.

45 In Fig. 1 of the drawing the piston or plunger 2 is presumed to be moving down to strike the working-tool 7. The valve 4 is down.

Live air from supply passage 8 will pass 50 through chamber 18 to groove 17 of the valve-box then flow down through passage 21 of the box to the upper chamber 14 above the piston or plunger 2 and act on the upper end of the latter to drive it down.

55 As the piston 2 moves down air from the lower chamber 15 of the cylinder may exhaust through port 10 until the piston covers it and may also pass up through channel 16 and escape around the reduced neck-part 28 of the valve, which at this moment is so positioned in the box as to connect the upper end of the channel 16 with the exhaust port 9. This exhaust from chamber 15 beneath the 60 piston or plunger prevents the pocketing of air between the lower end of the plunger 65

and the inner end of the working tool 7, so that the plunger can deliver a blow directly on the tool.

The valve 4 will be kept down (as in Fig. 1) notwithstanding the continuous delivery 70 of live pressure through passage 13 to the larger under or bottom side of the valve, because this live air simply passes on down passage 12 into the cylinder below the piston and then exhausts through port 10 to the 75 atmosphere.

Thus it will be understood that while constant live air is supplied by passage 13 under the valve 4, the pressure is not built up under said valve as long as the lower end of cylinder 80 channel 12 is open or uncovered by the piston 2.

When piston 2 has moved down in the cylinder far enough for its lower end to cover the entrance to channel 12, further exhaust of 85 the constantly supplied live air through passage 13 will be cut off and immediately the pressure in said channel 12 and flip-chamber 20 under the larger lower end of the valve 4 will build up (because of the constant supply 90 from 13 and no escape) and the valve 4 will then be moved up notwithstanding the constant pressure on the smaller upper end or head 27.

This operation thus places the valve in the 95 up-position shown in Fig. 2 of the drawing.

The piston or plunger now being down and the valve 4 being up, live air must be admitted beneath the plunger to lift the latter. This is effected as follows:

100 Live air from supply passage 8 will pass down through the central port 22 in the top of the valve then out into upper annular valve-groove 23 which latter, at this moment is in register with the upper end of lift-channel 16 while the lower end of said lift-channel 105 opens beneath the plunger when the latter is down in the cylinder.

To enable the plunger to move up, it is necessary to exhaust the pressure from its 110 upper side that is in chamber 14 and this exhaust (when the valve is up) is from the top of the chamber 14 through passage 21 to annular box-groove 17; then down around the reduced neck 28 of the valve to and 115 through the exhaust port 9 to the atmosphere.

When the plunger has moved up far enough to uncover exhaust port 10 and the lower end of channel 12, then the pressure from valve-chamber 20 and the under side of the valve 120 will escape by passing down through channel 12 into the cylinder chamber 15 beneath the plunger and out through exhaust port 10 to the atmosphere.

125 By thus relieving the pressure on the greater bottom area of the valve, the constant pressure on the smaller top or head 27, will push the valve down. The precise time at which this shifting of the valve takes place may readily be determined by the relative 130

sizes of the box passage 13 (Fig. 2) and the channel 12 (Fig. 1).

Having described my invention, I claim,—

1. In a percussive tool, a cylinder, a plunger, a valve-box having an upper annular chamber, an exhaust passage, a passage that extends through the box and opens into the upper end of the cylinder and another passage that is continually supplied with live motive fluid and which extends from the upper side of the box and opens at the center thereof near the bottom of the box, a valve having two pressure areas one greater than the other the lesser pressure area being subject to a substantially constant pressure and the greater pressure area of the valve being subject to a continuous pressure from the box-passage which is continuously supplied with live motive fluid which it delivers near the bottom of the box, means controlled by the plunger for confining the continuously supplied motive fluid until the valve is shifted, and means comprising a passage extending from the lower end of the cylinder up to and through the valve-box, said passage at its upper end being provided with a lateral and inwardly extending opening, adapted when the valve is lifted to register with an annular channel formed about the valve, which latter is in communication with a longitudinally extending passage formed in the valve body and in communication with the supply of live motive fluid.
2. In a percussive tool, a cylinder, a valve-box, a plunger in the cylinder, a valve in the box, said valve having differential areas, a cap fitting over and holding the box and cyl-

inder in rigid relation, means for supplying motive fluid in full volume to one side of the valve to subject the same to a substantially constant pressure, and means for supplying motive fluid in restricted amount to the other side of the valve to subject the latter side to continuous pressure, means for effecting a variation in the latter pressure to move the valve against the constant pressure, and means including an axial passage in said valve for supplying motive fluid for the non-working stroke of said plunger when said valve is shifted by said continuous pressure.

3. In a percussive tool, a cylinder, a valve-box, a plunger in the cylinder, a valve in the box, said valve having differential areas, a cap fitting over and holding the box and cylinder in rigid relation, means for supplying motive fluid in full volume to one side of the valve to subject the same to substantially constant pressure, means for supplying motive fluid in restricted amount to the opposite side of said valve to subject the latter side to continuous pressure, means controlled by the plunger for effecting a variation in the said continuous pressure to move the valve against the constant pressure, said valve having an axial passage extending from said constant pressure means and terminating in an annular groove on the exterior of the valve, and means registering with said groove on shifting of the valve by said continuous pressure for effecting the return or non-working stroke of said plunger.

In testimony whereof I affix my signature.
JOHN R. L. SANTOS.
